RELEASING DEVICE FOR AIR BRAKES

Application filed May 18, 1929. Serial No. 364,194.

This invention relates to a releasing device for air brakes particularly adapted for use in connection with railway trains, and has for its primary object to provide, in a manner as hereinafter set forth, a positive means for automatically releasing the brake applied to a car at rest, upon the application of a moving force to the car.

A further object of the invention is to provide a device for the purpose aforesaid, by means of which a train of cars equipped therewith may be expeditiously moved from a state of rest without likelihood of sliding the wheels of the cars, thereby materially reducing the wear on the wheels and increasing the life thereof.

A further object of the invention is to provide a device of the character aforesaid, by means of which the necessity of hand bleeding of brake cylinders may be eliminated, thereby materially reducing the expense and time in connection with switching operations in railroad yards.

With the foregoing and other objects in view, the invention consists of the novel construction, combination and arrangement of parts as hereinafter more particularly described, and as illustrated in the accompanying drawings wherein is shown an embodiment of my invention, but it is to be understood that such description and drawings are to be taken as illustrative and that the invention is intended to be limited only by the scope of the claims hereunto appended.

In the accompanying drawings in which like numerals are employed to designate like parts throughout the same:

Figure 1 is a vertical sectional view of my releasing device showing the relative position thereof with respect to a journal box and brake cylinder.

Figure 2 is a section taken on line 2—2 of Figure 1.

Figure 3 is a section taken on line 3—3 of Figure 1.

Figure 4 is a section taken on line 4—4 of Figure 1.

Figure 5 is a section taken on line 5—5 of Figure 1.

Figure 6 is a section taken on line 6—6 of Figure 1.

Figure 7 is a section taken on line 7—7 of Figure 1.

Referring to the drawings in detail, a journal box and brake cylinder are illustrated conventionally and designated respectively by the numerals 1 and 2. My invention consists of a fluid pressure controlling mechanism associated with the journal box and a fluid pressure controlled valve mechanism associated with the brake cylinder.

Positioned within the journal box is a journal flange 3 the periphery 4 of which is in the form of a circle, having a flat portion 5, whereby such periphery provides a cam. Secured to the journal box 1 in any suitable manner is a horizontally disposed cylinder 6, which is formed at its inner end with a reduced extension 7 extending through the wall 55 of the journal box. The extension 7 is hollow and extending therethrough is a piston rod 8. The rod 8 also extends through a suitable packing cap 9 threaded on the free end of the extension.

The outer end of the cylinder 6 is closed by means of a head 10, which is provided with a reduced extension 11 of cylindrical formation. The extension 11 is externally threaded for engagement with a cap 12 60 which provides a chamber 13 between the inner face of the outer end thereof and the outer end of the extension 11. The cap 12 is provided at its outer end with a cylindrical, externally threaded extension 14 for engagement with a coupling 15 for a fluid pressure line 16, which is adapted for connection with a train fluid pressure line, not shown. The interiors of the extensions 14 and 11 respectively open through the cap 12 and head 10 70 whereby communication is established between the line 16 and the interior of the cylinder 6.

One end of the piston rod 8 terminates within the cylinder 6 and spaced from such end, the rod is provided with a piston indicated generally by the numeral 17. In the embodiment herein illustrated the piston 17 consists of a circumferentially extending flange 18 on the rod 8, a flexible washer 19 75

bearing against the flange 18, a rigid washer 20 bearing against the washer 19, and a nut 21 threaded on the end of the rod 8 for maintaining the washers in position. The washer 19 is preferably formed of leather and is of greater diameter than the inner diameter of the cylinder 6. A peripheral portion of the washer 19 extends across the periphery of the washer 20, which is preferably formed of metal. The rod 8 is formed with a centrally disposed port 22 which opens at one end through the outer end of the rod 8 and extends throughout a portion of the length of the latter in a longitudinal direction. The opposite end of the port 22 merges into a right angularly disposed port 23 which opens through the peripheral face of the rod 8 into the interior of the cylinder 6. The outer ends of the ports 22 and 23 respectively are disposed on opposite sides of the piston 17.

Extending through the head 10 and extension 11 is a plunger 24 which is provided at its inner end with a head 25 disposed within the cylinder 6 and formed with a beveled forward face 26. The outer end of the port 22 is flared as indicated at 27 to provide a seat for the beveled face 26. The plunger 24 is provided at its outer end with a head 28 which is disposed within the chamber 13 and formed with a beveled forward face 29. The opening through the extension 11 is flared at its outer end as indicated at 30 to provide a seat for the beveled face 29. Encircling the plunger 24 is a coil spring 31, the respective ends of which abut the rear face of the head 25 and a shoulder 32 formed in the wall of the opening through the head 10.

Leading from the cylinder 6, adjacent the inner end thereof, is a fluid pressure conducting line 33, which is connected with and opens through the head 34 of a vertically disposed cylinder 35. The cylinder 35 is connected with the brake cylinder 2 by means of a suitable pipe 36 and is closed at its lower end by means of a head 37. Disposed within the cylinder 35 is a piston 38 from the lower face of which depends a substantially bell shaped projection 39. The piston 38 is adapted to reciprocate between the head 34 and a shoulder 40 formed in the inner wall of the cylinder 35. Extending vertically through the head 37 is an opening 41, the upper end of which is encircled by a seat 42 for a ball valve 43. When the piston 38 is positioned against the shoulder 40, the projection 39 bears against the ball valve 43 and maintains the latter in position on the seat 42 to close the opening 41. The lower face of the head 34, centrally thereof, is substantially dome shaped as indicated at 44, and circumferentially of the dome shaped portion 44, the lower face of the head 34 is flat, as indicated at 45, to provide a seat for the upper face of the piston 38. Extending

through the head 34 and opening through the dome shaped portion of its inner face is an opening 46 which is provided with an escape valve 47. The inner end of the opening 48 which establishes communication between the line 33 and the interior of the cylinder 35 is disposed centrally of the dome shaped portion 44 of the inner face of the head 34.

In the operation of my releasing device, a fluid pressure medium such as compressed air is admitted thereto through the line 16. During such periods as the piston rod 8 is in engagement with the curved portion of the cam 4, such air passes to the interior of the cylinder 6, where it is obstructed by the piston 17. When the flat portion 5 of the cam 4 is brought into engagement with the piston rod 8, the plunger 24 is moved inwardly by the action of the spring 31, to force the beveled face 29 against the seat 30, thereby preventing any more air from passing the chamber 13. At the same time, the pressure of the air against the piston 17 forces the seat 27 away from the beveled face 26, thereby permitting the air to pass through ports 22 and 23 to the inner end of the cylinder 6, from where it is conducted through the line 33 to the cylinder 35. A check valve, indicated conventionally at 49, is provided in the line 33 which permits the passage of air through the line in the direction of the cylinder 35 but prevents the passage of air therethrough in the direction of the cylinder 6. When the curved portion of the cam 4 is again brought into engagement with the piston rod 8, the seat 27 is moved into engagement with the beveled face 26 and the plunger 24 is forced outwardly against the compression of the spring 31 to move the beveled face 29 away from the seat 30, whereby more air is admitted to the cylinder 6.

When air is admitted through the line 33 to the cylinder 35, the piston 38 is forced downwardly until the projection 39 rests on the ball valve 43, whereby the latter is maintained on its seat 42. So long as the cam 4 continues to rotate, air will be admitted to the cylinder 35 as above set forth, each time the flat portion 5 of the cam 4 is brought into engagement with the piston rod 8, and such air is permitted to leak from the cylinder 35, through the escape valve 47. Upon the cam 4 being brought to a state of rest, no more air will be permitted to pass the piston 17, and the escape valve 47 is preferably so adjusted as to permit the air within the cylinder 35 to escape in approximately sixty seconds, after which the air within the brake cylinder 2 will force the piston 38 upwardly to remove the projection 39 from the ball valve 40. If desired, the adjustable valve 47 may be omitted and the opening 46 formed of a size suitable to provide an escape valve. The air within the brake cylinder 2 will con-

tinue to brake the car in the usual manner so long as the car remains at rest but as soon as a moving force is applied to the car, the shock imparted thereto will jerk the ball valve 43 from its seat, thereby permitting the air to escape from the brake cylinder 2, through the opening 41 in the head 37.

It is thought that the many advantages of a releasing device in accordance with this invention will be readily apparent, and although the preferred embodiment of the invention is as illustrated and described, it is to be understood that various changes in the details of construction may be resorted to, so long as such changes fall within the scope of the invention as defined in the appended claims.

What I claim is:

1. In fluid pressure brakes for railway trains, a releasing device for the brake cylinder comprising a valve mechanism for establishing communication between the brake cylinder and the atmosphere and including a valve normally closing such communication and shiftable to open position by shock imparted to the train when at rest upon the application of a moving force to the latter, said mechanism further including a pressure operated means acting on said valve to maintain the same in closing position during the application of the brakes, a fluid pressure controlling mechanism for communication with the fluid pressure line of the train and including a cam and spring operated valved means for intermittently establishing such communication when the train is in motion, a fluid pressure conducting line leading from said pressure controlling mechanism to said valve mechanism, said valved means having a valve controlled port to provide intermittently for the passage of fluid through said conducting line, and an escape valve for said valve mechanism to relieve the pressure from said pressure operated means when the train is at rest.

2. In fluid pressure brakes for railway trains, a releasing device for the brake cylinder comprising, a valve mechanism for establishing communication between the brake cylinder and the atmosphere and including a valve normally closing such communication and shiftable to open position by shock imparted to the train when at rest upon the application of a moving force to the latter, said mechanism further including a piston for engagement with said valve, a fluid pressure controlling mechanism for communication with the fluid pressure line of the train and including a cam and spring operated valved means for intermittently establishing such communication when the train is in motion, a fluid pressure conducting line leading from said pressure controlling mechanism to said valve mechanism, said valved means having a valve controlled port to provide intermitt-

tently for the passage of fluid through said conducting line for maintaining said piston in engagement with the valve in said valve mechanism when the train is in motion, and an escape valve for said valve mechanism to relieve the pressure from said piston when the train is at rest.

3. In fluid pressure brakes for railway trains, a releasing device for the brake cylinder comprising, a valve mechanism for establishing communication between the brake cylinder and the atmosphere and including a valve normally closing such communication and shiftable to open position by shock imparted to the train when at rest upon the application of a moving force to the latter, said mechanism further including a pressure operated means acting on said valve to maintain the same in closing position during the application of the brakes, a fluid pressure controlling mechanism for communication with the fluid pressure line of the train and including a spring controlled valve member normally closing such communication and further including a cam operated member for actuating said spring controlled valve member to establish such communication intermittently when the train is in motion, a fluid pressure conducting line leading from said pressure controlling mechanism to said valve mechanism, said cam operated member having a port intermittently closable by said valve member to provide intermittently for the passage of fluid through said conducting line, and an escape valve for said valve mechanism to relieve the pressure from said pressure operated means when the train is at rest.

4. In fluid pressure brakes for railway trains, a releasing device for the brake cylinder comprising, a valve mechanism for establishing communication between the brake cylinder and the atmosphere and including a valve normally closing such communication and shiftable to open position by shock imparted to the train when at rest upon the application of a moving force to the latter, said mechanism further including a pressure operated means acting on said valve to maintain the same in closing position during the application of the brakes, a fluid pressure controlling mechanism for communication with the fluid pressure line of the train and including a spring controlled valve member normally closing such communication, a slidable member for actuating said valve member to establish such communication intermittently, and further including a cam rotatable with the wheels of the train for operating said slidable member, a fluid pressure conducting line leading from said pressure controlling mechanism to said valve mechanism, said slidable member having a port intermittently closable by said valve member to provide intermittently for the passage of fluid through said conducting line, and an escape valve for

said valve mechanism to relieve the pressure from said pressure operated means when the train is at rest.

5. In fluid pressure brakes for railway trains, a releasing device for the brake cylinder comprising, a valve mechanism for establishing communication between the brake cylinder and the atmosphere and including a valve normally closing such communication and shiftable to open position by shock imparted to the train when at rest upon the application of a moving force to the latter, said mechanism further including a pressure operated means acting on said valve 10 to maintain the same in closing position during the application of the brakes, a fluid pressure conducting line leading to said valve mechanism, a cam operated pressure controlling mechanism for intermittently passing fluid from the fluid pressure line of the train to said conducting line when the train is in motion, and an escape valve for said valve mechanism to relieve the pressure from said pressure operated means when 15 the train is at rest.

6. In fluid pressure brakes for railway trains, a releasing device for the brake cylinder comprising, a valve mechanism for establishing communication between the brake cylinder and the atmosphere and including a valve normally closing such communication and shiftable to open position by shock imparted to the train when at rest upon the application of a moving force to the latter, 20 said mechanism further including a pressure operated means acting on said valve to maintain the same in closing position during the application of the brakes, a fluid pressure conducting line leading to said valve mechanism, a cam operated pressure controlling mechanism for intermittently passing fluid from the fluid pressure line of the train to 25 said conducting line when the train is in motion, and an escape valve for said valve mechanism to relieve the pressure from said pressure operated means when the train is at rest, said valve mechanism including a cylinder having its interior in communication with the interiors of the brake cylinder 30 and said conducting line, and a piston disposed within the cylinder between the points of said communication and constituting said pressure operated means.

7. In fluid pressure brakes for railway trains, a releasing device for the brake cylinder comprising, a valve mechanism for establishing communication between the brake cylinder and the atmosphere and including a valve normally closing such communication and shiftable to open position by shock imparted to the train when at rest upon the application of a moving force to the latter, said mechanism further including a pressure operated means acting on said valve to maintain the same in closing position during the

application of the brakes, said releasing device further comprising a cam for rotation with the wheels of the train, a piston rod engaging the cam, a cylinder into which the piston rod slidably extends, a piston carried by the rod and disposed within the cylinder, means to provide a fluid pressure conduit leading to said cylinder at one side of the piston, a fluid pressure conducting line leading from the cylinder at the opposite side of the piston to said valve mechanism, said piston rod having a port disposed within the cylinder and opening at opposite sides of the piston, a spring controlled valve member normally closing said conduit and actuated by the piston rod to intermittently open the conduit, said valve member coacting with the piston rod to close said port when the conduit is open, and an escape valve for said valve mechanism to relieve the pressure from said pressure operated means when the train is at rest.

In testimony whereof, I affix my signature hereto.

PERLEY E. FULWIDER.
